Simon E. Schroeder, Inventor.
BY W. D. Tefft, Atty.

UNITED STATES PATENT OFFICE.

SIMON E. SCHROEDER, OF MINIER, ILLINOIS.

WASHING-MACHINE.

1,227,840.

Specification of Letters Patent.

Patented May 29, 1917.

Application filed October 9, 1915. Serial No. 55,080.

To all whom it may concern:

Be it known that I, SIMON E. SCHROEDER, a citizen of the United States, residing at Minier, in the county of Tazewell and State of Illinois, have invented certain new and useful Improvements in Washing-Machines, of which the following is a specification.

This invention has reference more particularly to that type of washing machine in which the washing element is operated by power and is capable of being moved to positions over several tubs and in each position to be connected with the power driving mechanism.

15 The object of my invention is to provide improved means for supporting the washing mechanism in its different positions and a further object is to provide suitable means for operating the washing mechanism in its 20 different positions and also permitting movement of the said mechanism to said positions.

A further object is to provide a compact structure in which the number of exposed 25 operating parts is reduced to a minimum and in which the parts so exposed are positioned close against the machine and are so constructed that they are not liable to injure anyone.

30 In the accompanying drawing forming a part of this application—

Figure 1 is a side elevation of my washing machine showing my invention;

Fig. 2 is a plan of the same;

35 Fig. 3 is a detail of a clutch, and

Fig. 4 is a plan of one of the clutch portions shown in Fig. 3.

A represents the usual platform of a washing machine having mounted on end a 40 tub B and at the other a tub C. Arising from the platform between the tubs is a shaft D having suitable bearings, E, F, one on the tub and one on the platform, or otherwise suitably placed. G is an arm beneath the platform secured to the shaft D and oscillated by means of a pitman H connected in suitable manner to a gear J, for example, carried on the platform and with

which a pinion gear K meshes, the latter being carried in bearings L and rotated by 50 any source of power.

The upper end of the shaft D carries a clutch portion M consisting of a plate N, for example, having a recess O at opposite sides of the shaft, as shown in Fig. 4. The 55 shaft D is extended above the clutch portion M N and is adapted to receive a second clutch portion P which includes a plate Q having two oppositely disposed lugs R for engaging the recesses O in the other part 60 described. S is a shaft portion carrying the clutch portion P Q, its upper end carrying an arm T adapted to oscillate in a horizontal plane, oscillation being imparted through the shaft D and the clutch portions 65 and the mechanism previously described.

U represents a portion of a stationary top of the wash tub B, together with a drain board V as a part of the same, and W is a removable top portion which, when lying 70 upon the tub B, fits the top U V. Extending centrally through the removable top W and having a bearing therein is a shaft 2. This shaft 2 at its lower end carries any usual type of agitator 3 and its upper end outside 75 the tub has affixed to it a pinion 4 with which meshes a gear-segment 5 mounted on said top W or rather upon a casting W' of said top which forms the bearing for said pinion 4 and said segment.

6 is a pitman pivoted at one end to the said segment. The other end of the pitman is pivoted to the outer end of the rock arm T before described.

At that end of the platform upon which the tub C is mounted there is erected a support 7 bearing at its upper portion a shelf 8 which is of substantially the same height as the top portion U of the tub B as shown in Fig. 1. Preferably said shelf 8 is provided with a recess 9 in its edge facing the tub B, there being a supporting ledge beneath it. In Fig. 2 it will be observed that the top W has been lifted from the tub B and placed above the tub C the recess 9 receiving one of the straight edges of the

same, on that edge which while on the tub B adjoined the straight portion of the fixed part U. It will also be observed that the ledge 10 is a support for the top W, the recess 9 acting therewith to hold the top firmly in position during the oscillation of the agitator.

The clutch portions M, N, P, Q, together with the top W, can be lifted entirely away from the tub B so that the agitator 3 can be withdrawn from said tub, whereupon it can be placed upon the shelf 8 as shown in Fig. 2, the clutch portions being again brought into engagement so that oscillation of the shaft D will be transmitted to the agitator within the tub C as well as within the tub B.

I have described the mechanism for operating the agitator as one of the ways of imparting the oscillating movement but other means may be used as may be understood, my invention residing in the swinging lid or cover to overlie either tub and with which is included an operating mechanism through a common support, there also being included a support for the lid or cover when above the tub C whether said support is a part of the platform or not.

What I claim is:

1. In a device of the class described, the combination of a platform adapted to support a plurality of receptacles, a movable supplemental frame forming a cover for any one of said receptacles, means on the main frame for supporting the supplemental frame in a plurality of operating positions parallel with the main frame, power driving mechanism on the main frame, operating mechanism on the supplemental frame adapted to enter a receptacle when said supplemental frame is positioned thereover, and separable power transmission parts adapted to be engaged when the supplemental frame is in any of the operating positions and adapted to be disengaged when the supplemental frame is moved from the operating positions.

2. In a device of the class described, the combination of a main frame, a removable supplemental frame with an operating mechanism thereon, means at each end of the frame and intermediate of the ends of the frame for supporting the said supplemental frame in operating position at either end of the main frame, power driving mechanism on the main frame and transmission mechanism intermediate the ends of the main frame connecting the power driving mechanism and the said operating mechanism, said transmission mechanism being provided with separable parts, said parts being adapted to be separated when the sup-

plemental frame is removed and adapted to be in engagement when the supplemental frame is in either position on the main frame.

3. In a device of the class described, the combination of a platform adapted to support a plurality of receptacles, a supplemental frame, operating mechanism on the supplemental frame, means on the platform for supporting the supplemental frame in a plurality of positions parallel with the platform and over one of said receptacles with the operating mechanism inserted therein, power driving mechanism under the platform, and power transmission mechanism extending upward through the platform, said transmission mechanism including separable parts adapted to be disconnected when the supplemental frame is removed and adapted to engage when the supplemental frame is in any of its operating positions.

4. In a device of the class described, the combination of a platform adapted to support a plurality of receptacles, a movable supplemental frame designed to be shifted to form a cover for any one of said receptacles, operating mechanism carried by the cover or supplemental frame and extending into the covered receptacle, an upright driving mechanism on the main frame, and separable clutch members forming a driving connection between the upright mechanism and the operating mechanism, and adapted to be disengaged when the cover is removed and adapted to be engaged when the cover is in position above any receptacle.

5. In a device of the class described, in combination, a platform, a plurality of container members thereon, a removable supplemental frame forming a cover for any of said container members, operating mechanism on said frame or cover, means for supporting said frame and mechanism interchangeably in superimposed operating relation with either of said container members, power driven mechanism on the main frame, separable power transmission parts adapted to be engaged when the supplemental frame is in any of its operating positions and adapted to be disengaged when the supplemental frame is moved from the operating positions.

6. In a device of the class described, in combination, a platform adapted to support thereon a plurality of container members one of which is fixed, a removable supplemental frame, means on the fixed container member and at the opposite end of said platform for supporting said frame interchangeably in superimposed operating relation with either of said container members,

power driven mechanism on the main frame including an upright driven shaft, operating mechanism on the supplemental frame including a vertical driven shaft, separable 5 power transmission parts respectively upon the driven shaft and the shaft of the supplemental frame adapted to be engaged when the supplemental frame is in any of its operating positions and adapted to be

disengaged when the supplemental frame is 10 moved from the operating positions.

In testimony whereof I have affixed my signature in presence of two witnesses.

SIMON E. SCHROEDER.
